(71) Applicant: **Hallmark Cards, Incorporated**, Kansas City, MO (US)

* cited by examiner

(72) Inventor: **Melanie Bridges**, Mission, KS (US)

Primary Examiner — Caron D Veynar

Assistant Examiner — Abraham Bahta

(73) Assignee: **Hallmark Cards, Incorporated**, Kansas City, MO (US)

(74) *Attorney, Agent, or Firm* — Shook, Hardy & Bacon L.L.P.

(**) Term: **14 Years**

(57) **CLAIM**

(21) Appl. No.: **29/486,537**

(22) Filed: **Mar. 31, 2014**

DESCRIPTION

(51) **LOC (10) Cl.** **19-01**

FIG. 1 is a front right perspective view of the bundled greeting

(52) **U.S. Cl.**

card and envelope of the present invention;

USPC **D19/2**

FIG. 2 is a front plan view thereof;

(58) **Field of Classification Search**

FIG. 3 is a rear plan view thereof;

CPC B65D 33/00; B65D 85/505; B29C 66/71

FIG. 4 is a left side elevation view thereof;

USPC D19/1-12, 20-34; 40/124.01-124.15,

FIG. 5 is a right side elevation view thereof;

40/672, 661, 726, 776, 617, 633; 229/72,

FIG. 6 is a bottom side elevation view thereof; and,

229/92, 92.1, 299.01; 206/449; D21/385;

FIG. 7 is a top side elevation view thereof.

D20/10, 22, 40, 27, 42, 11;

The evenly spaced broken lines shown in the drawings are

D14/435-437; D24/231; 705/2-3;

directed to environment, are for informational purposes only,

283/72, 74, 75, 103, 105, 106

and form no part of the claimed design.

See application file for complete search history.

The surface shading lines on the claimed portion are provided
